BEAM COMPASS

Ed Laxo, Riverside, Ill.

Application October 27, 1941, Serial No. 416,725

5 Claims. (Cl. 33—160)

This invention relates to stability in refined adjustment of engineering tools.

This invention has utility when incorporated in manufacture from strip stock or ribbon, bar, and rod type of refinement in characteristics for locating and maintaining accuracy of dimension.

Referring to the drawings:

Fig. 1 is a plan view of a case in which the tool is assembled;

Fig. 2 is a view, with parts broken away, of the open case showing the grouping of the elements for the tool;

Fig. 3 is a view of the marker carrying pointer, from the end or side thereof from the right of Fig. 8, and having the supplemental minor adjustment;

Fig. 4 is a view from the opposite side or end of the marker, on the line IV—IV, Fig. 8;

Fig. 5 is a view of the center pivot or holding pointer at end or side elevation, showing the beam in section from the line V—V, Fig. 8;

Fig. 6 is a view of the opposite side or end of the pivot pointer on the line VI—VI, Fig. 8;

Fig. 7 is a view of an end elevation of the coupling for beam extension on the line VII—VII, Fig. 9;

Fig. 8 is an assembly, with parts broken away, of the beam compass showing the pivot carrier or holder and the marker carrier;

Fig. 9 is a view of the extension beam compass with the coupling assembly having the pivot carrier at the left on the line IX—IX, Fig. 5, and the marker carrier on the line IX—IX, Fig. 3, with parts of the beam broken away;

Fig. 10 is a fragmentary view of the beam coupling on the line X—X, Fig. 7; and

Fig. 11 is a section on the line XI—XI, Fig. 9, of the marker carrier.

Strip or ribbon stock may comprise channels 1, 2, 3, flat bars or beams 4, 5, spacer arms 6, 7 (Fig. 2), spacers 8, 9 (Fig. 9), 10 (Fig. 10), for the cheeks of the channels, rod stock assembly pins or rivets 11 (Fig. 9), arm carrying pins 12, clamp screw stems 13, adjusting screw stems 14, and, also from rod stock, nut 15, screw heads 16 (Figs. 3, 5, 9), and special screw head 17 with swivel ball terminus 18 (Fig. 6). In the assembly set-up there thus remains merely rod stock of helical spring 19 (Fig. 9).

In the carrying out of the invention herein, this strip stock is shaped, and in the assembly, by provision of openings, there is developed a light weight, substantial, geometrical instrument adapted for accurate use by draftsmen and in tools of measurement and marking. The flat beam 4, say for a beam compass, may have mounted thereon as its pivot the channel 2 having its root side 20 with parallel cheeks 21 therefrom, having the spacer 8 therebetween,

there being clearance from the spacer to in-turned ears 22 providing a ledge or point at one end, opposing ledge 23 on the root 20 at the opposite end of way 24 through this carrier, 5 wherein the spacer 8 is anchored by rivets 11 opposite the ledge points 22, 23, thereby to support threaded screw 14 having its head 17 fixed or pressed thereon. This intermediate locking screw 14 thereby provides in this carrier a three 10 point anchorage with the bar 4 of this beam compass, which three points are in the maximum dimension on narrow edges of this flat beam. This means a maximum dimension distance of the three points from each other in substantial 15 holding of this beam between the pair of cheeks 21, which snugly rest thereagainst. At slight clearance as to this way 24 between the cheeks 21 is rivet or pivot 12. The arm 6 on the pivot 12 has its side 25 ride against the inner side of the root 20 and holds this arm against any shifting 20 relatively to this carrier. This arm 6 as extending below the root 20 has therein adjusting screw 13 with the head 16 between fork portion 26 providing free ends 27. As the screw 13, 16, is adjusted, these way-providing portions 25 27 may clamp pointer tool 28 in adjusted position away from the beam 4, whether such be for pivot point 29 or more tapering point 30 as in active position for the pivot. In this operation 30 of the beam for this carrier to serve as the center or pivot, the spheric portion 18, as swiveled on the terminus of the screw 14 having the head 17 fixed therewith, permits this holding of the instrument during the arc or swinging operation 35 independently of tendency to disturb the setting for this clamping screw 14.

In the event the tool be used in a dimension wherein the one bar, either the bar 4 or the bar 5 is sufficient in extent, then a marker or complementary pointer carrier may be placed thereon. This complementary channel device 1 likewise has root 31 opposing cheeks 32, spacer 9, rivets 11 to anchor such spacer between the cheeks, ledges 22 and 23, and pivot rivet 12. 40 Accordingly, the general assembly very much approaches a duplication of that for the pointer, the distinction being that the pin 12 is located away from the root 31 instead of adjacent thereto as with the pivot pointer. Furthermore, the arm 7 is pivoted on this pin or anchor 12. This arm 7 has forked free end 33 with the clamping screw 13 therebetween for adjusting the holding way 27 to carry marker tool 34, say a lead marker, crayon, or even inking device, or caliper pointer.

In the functioning of this tool, adjustment of the respective carriers for the pointers along the beam or beams may be by a definite anchorage or locking, that of this marking carrier being by the marking screw 14, 16, at the intermediate

point between the ledges 22, 23. For extreme fineness of adjustment, the location between the pointer 29 and the marker or pointer 34 may on occasion be one as to which there is desired a minute further adjustment. To such end, between the forks 33, pin 35 may anchor threaded stem 36 for extending through opening 37 in the root 31, there to receive the adjusting nut 15. Between this arm 7 and this root 31 on this threaded rod 36 is compression helical spring 19. Accordingly, by this screw 15 there is refinement of micrometer adjustment in the location of the point 34 and its spacing as to the point 29. With this spring 19 of a degree of stiffness there is no tendency to wobble nor is there such swing or accuracy disturbance feature between the respective channel carriers as mounting these pointers with the bar.

For a wider range of adjustment and retention of accuracy, a plurality of the bars may be adopted instead of extreme extension for one bar, thereby avoiding the cumbersome features of a long instrument when there may be desire to use for a short range as the shorter bar 5 readily adapts thereto. For the extension beyond that of the longer bar 4, there may be adopted hereunder a coupling, herein shown as channel member 3 having root 40 (Fig. 10) with spacer 10 between cheeks 41. In addition to anchoring the rivets 11 at the spacer 10 there is stop pin 42 determining the insert distance in way 43 for the respective bars 4, 5. There is here likewise a positive anchoring against side shift or wobble due to the clamping screws 14, 16, acting upon a narrow edge of the bar stock a major distance from the opposing edge as against the root 40.

This tool set-up may be one readily portable, wherein there is provided case having lower section 44, lid 45, hinges 46 therebetween, and catches 47 to lock the case in closed position. This case base portion 44 has seat portions 48, 49, therein for the respective bars, seat portion 50 for the coupling, seat portion 51 for the marker carrier, and seat portion 52 for the pivot carrier.

Accordingly, in the operation hereunder, the engineer or operator may open the case 44, 45, select the bar 4 or 5 for the range of operation convenient. In the event such is for short radius, the bar 5 may have placed thereon the pointer carrier 2 with the nut 14, 17, locked to clamping position therewith, the pointer 29 having the desired placement and clamping through the action of its clamping screw 13, 16. Next in order is the slipping of the marker screw on the remote portion of the bar 5 with its clamping screw 14, 16, in the approximate adjusted position along the bar for the radius sought between the pointer 9 and the marker 34, each as projecting narrowwise away from the bar in said approximate plane of the wide range of the bar. For micrometer refinement in locating the pointer 34, the nut 15 may be adjusted. With this determination for the arc or extent or curve or circle desired, the operator may grasp the spherical portion 18 above the pointer 29 of the pivot and with the other hand swing the bar 4 say by holding adjacent the carrier 1.

What is claimed and it is desired to secure by Letters Patent is:

1. For a beam rider of a drafting instrument beam, wherein the rider provides a leg compris-

ing a channel forming an opening through which opening the beam extends, said channel depending from the opening with a pair of parallel cheeks providing ledges adjacent the beam to form a beam bearing at one side of the opening, a set screw through the intermediate portion of the rider at the opposite side of the opening from the ledges for engaging the beam to hold the beam against the ledges, of a pin between the cheeks and spaced from the beam on the side away from the set screw, a spacer arm on the pin and nesting between the cheeks and provided with a forked free end portion, and a fork adjusting screw, said fork having offset portions forming a seat for a pointer tool to be clamped by the screw.

2. For a beam rider of a drafting instrument beam, wherein the rider provides a leg comprising a channel forming a way through which way the beam extends, said channel being fixed with the rider in forming said way to guide the beam, of a spacer arm, and a pivot pin connection for mounting the arm in the channel to extend away from the beam guide way, said arm having a forked clamp for mounting a pointer tool in adjusted position as to the channel.

3. For a beam rider of a drafting instrument beam, wherein the rider provides a leg comprising a channel having therethrough a guide way for the beam, said channel being fixed with the rider in forming said beam guide way, of a spacer arm, and a pivot pin connection for mounting the arm in the channel to extend away from the beam guide way, said arm having a forked clamp for mounting a pointer tool in adjusted position as to the channel, there being a connecting root portion at the channel and extending away from the beam and parallel to the arm.

4. For a pair of beam riders for a drafting instrument beam, adapted to be adjusted along the beam, wherein each rider comprises a leg including a parallel-cheek-providing channel fixed with the rider to extend about the beam and form a guide way for the beam, of a spacer arm, and a pin connection between the cheeks and spaced from the beam for mounting the arm to extend away from the beam guide way, said arm having a forked clamp for mounting a pointer tool in adjusted position as to the channel, one of said riders being adapted for centering the instrument and having a connecting root portion at the channel between the cheeks and extending away from the beam and parallel to the arm for the arm to nest therein.

5. For a pair of beam riders for a drafting instrument beam, adapted to be adjusted along the beam, wherein each rider comprises a leg including a parallel-cheek-providing channel fixed with the rider to extend about the beam and form a guide way for the beam, of a spacer arm, a pin connection between the cheeks and spaced from the beam for mounting the arm to extend away from the beam guide way, said arm having a forked clamp for mounting a pointer tool in adjusted position as to the channel, one of said riders being adapted for a marker and having a connecting root portion for the channel extending integral with and between the cheeks and extending away from the beam and parallel to the arm, and an adjusting screw for spacing the arm from said root portion.
